UNITED STATES PATENT OFFICE.

WILLIAM C. GRAY, OF PHILADELPHIA, PENNSYLVANIA, ASSIGNOR OF ONE-HALF
TO WILLIAM GOLDSTEIN, OF PHILADELPHIA, PENNSYLVANIA.

VALVE FOR INTERNAL-COMBUSTION ENGINES.

Application filed February 5, 1926. Serial No. 86,168.

My invention relates to a novel construction of a valve for internal combustion engines, which is capable of use with L head, overhead or other type of valve operating devices, my novel valve comprising an imperforate piston, which is reciprocable in a tubular extension preferably cast on the upper portion of the engine cylinder and provided with ports which are opened and closed at the proper intervals, there being two valves, as an inlet and exhaust valve for each cylinder. In the conventional type of poppet valves now generally employed, there is always more or less noise present on account of the impact of the valve upon its seat, and in addition very powerful springs are required in order to seat these poppet valves at the proper periods. In addition poppet valves of the above character soon become fouled with carbon, so that in order to attain the best results it is necessary for the valve seats of valves of this general character to be frequently reground. By my present invention wherein the pairs of imperforate valves slide in tubular open ended, ported housings or valve guides which are preferably cast on the tops of the engine cylinders, I provide a novel valvular construction, which is noiseless in operation, which cannot become fouled with carbon and wherein I am enabled to employ springs of a very moderate tension. In my novel construction of cylindrical valve no pressure is exerted against the wearing surface of the valve or its seat and its design further prevents any deleterious accumulation of foreign matter or carbon.

To the above ends, my invention consists of a novel construction of cylindrical valve, slideable in a ported tubular extension or housing, whereby I am enabled to produce a silently operating valve, which does not require grinding or removal of carbon and which does not require the use of heavy springs of the character commonly employed on poppet valves now in use.

It further consists of other novel features of construction and advantage, all as will be hereinafter fully set forth and pointed out in the specification and claim appended hereto.

For the purpose of illustrating my invention I have shown in the accompanying drawings several forms thereof which are at

present preferred by me, since the same have been found in practice to give satisfactory and reliable results, although it is to be understood that the various instrumentalities of which my invention consists can be variously arranged and organized and that my invention is not limited to the precise arrangement and organization of the instrumentalities as herein shown and described.

Figure 1, represents a plan view of the top of a cylinder block provided with valves embodying my invention, three of said cylinders with their inlet and exhaust valves being shown.

Figure 2, represents a vertical section on line 2—2, Fig. 1, said section being taken through an inlet valve, and certain of the parts being shown in elevation.

Figure 3, represents, a vertical section on line 3—3 of Fig. 1, the section being taken through an exhaust valve, and certain of the parts being shown in elevation.

Figure 4, represents a vertical section on line 4—4 Fig. 1, showing the arrangement of the inlet and exhaust valves and their adjuncts.

Similar numerals of reference indicate corresponding parts.

1 designates an engine cylinder of an internal combustion engine having a water jacket 2 and the piston 3 which actuates the connecting rod 4 which rotates the crank shaft 5, the foregoing parts being of the usual construction. The top of the horizontal wall 6 of each cylinder or the cylinder block is machined, so that the head 7 can fit accurately thereon, said head being provided with the water jacket 8, the horizontal top wall 9 and the pendant vertical outer wall 10, which two latter walls inclose my novel valve mechanism. It will be understood that my novel valve mechanism can be applied to a four, six, eight or any multi-cylinder engine and said cylinders can be cast en bloc or can be arranged to stand vertically or inclined or in line or may be oppositely disposed if desired. In the present invention I have shown in Fig. 1 but three cylinders, each being provided with my novel inlet and exhaust valves, but it will be understood that my novel invention is equally applicable to any multiple cylinder internal combustion engine.

At the side of each engine cylinder I cast

or otherwise form the elongated inlet chamber 11 for the incoming fuel, each inlet chamber being separated from the adjacent elongated exhaust chamber 12, by partitions 13, as will be understood from Figs. 1 and 4. 14 designates the bottom wall of inlet chambers 11 from each of which extends upwardly the valve rod guide 15, in which the inlet valve rod 16 reciprocates. Upon the upper end of the inlet valve rod 16 is secured the cylindrical inlet piston valve 17, which reciprocates in the tubular open ended extension, housing or casing 18, which is provided with the ports 19, the lower end of the bore 20 of said valve housing, communicating at all times with said chamber 11. The inlet valve 17 is in the form of a cylinder reciprocable in the bore 20 of the integral, tubular, extension 18. The inlet valve rod 16 is threaded at its lower portion as at 22 and carries a nut 21 and a washer 23, against the top of which abuts the bottom of the spring 24, the upper end of said spring abutting on the bottom of the partition 14. The lower end of the inlet valve rod 16 is guided in a suitable bushing or stuffing box 25, and carries at its lower end a roller 26, which bears upon the cam 27 fast on the cam shaft 28, as will be understood from Fig. 2. The fuel is introduced into the inlet chamber 11 by means of the inlet manifold 29, which is provided with branches 30, which communicate with the inlet chambers 11 as will be understood from Figs. 1 and 2. The construction of the exhaust piston valves 31, exhaust valve rods 32, the open ended tubular extensions 33 having the ports 34, the exhaust valve rod guide 35, the spring 36 therefor, the cam shaft 28 with its cam 38, the roller 39 and the guide or stuffing box 40, seen in Fig. 3, is substantially the same as already described with respect to Fig. 2. The exhaust piston valve 31 controls the exhaust ports 34, which permit the exhaust to flow into the exhaust chamber 12, and thence through the nipples 41 into the exhaust manifold 42 which latter is constructed so as to surround and heat the intake manifold 29. The spark plugs 43 are of the usual construction as their function is well known, it is not necessary to describe them in detail. The cam shaft 28 can be rotated by any suitable or conventional mechanism and it will be apparent from Fig. 2 that when the inlet piston valve is in its uppermost position seen therein, that the fuel has entered the inlet chamber 11, and passed thence through the ports 19 to the explosion chamber in the upper end of the cylinder and the explosion having taken place, the piston 3 has been driven downwardly into the position seen in Fig. 2.

During the period of said explosion and during the descent of the piston, the exhaust piston valve 31 assumed the position

seen in Figure 3 thereby closing the ports 34. As the piston 3 begins to ascend from the position seen in Figs. 2 and 3, the inlet valve 17 descends, so as to close the ports 19 and the exhaust valve 31 ascends, so as to open the ports 34 which are shown closed in Fig. 3. As the piston 3 continues its ascent, the exhaust takes place through the ports 34, the exhaust chamber 12, the nipple 41 and the exhaust manifold 42. The timing of the valves 17 and 31 can be readily adjusted so that said valves may open and close at slightly different predetermined periods, as is evident, and as the general mode of operation of engines of this general character is well known, the operation need not be described in greater detail. Since the bore of the tubular extensions 18 and 33 aligns with the bore of the valve rod guides 15 and 35, it will be apparent that when the head 7 is removed the valves 17 and 31 and their adjuncts can be readily assembled in position. As there is no pounding or hammering present during the reciprocation of the inlet valve 17 and the exhaust valve 31, it will be apparent that the action of said valves is noiseless and that there is no opportunity for said valves or their adjuncts to be fouled by carbon deposits. The springs 24 and 36 which control the movement of the inlet and exhaust valves 17 and 31 need have only a slight tension sufficient to overcome friction as no pressure is exerted against wearing surfaces of the valves or their seats which are cylindrical in form. The valves are so constructed that their design prevents the accumulation of foreign matter in carbon or other form thereon. It is further obvious that there is no necessity at any time for grinding the valves or their seats as is necessary at frequent intervals in the case of poppet valves now in use.

It will be evident that parts of engines of various conventional types can be readily made to include my novel valve design during machining or a completed engine can at small expense be modified to receive my novel valve mechanism. The tubular open ended inlet and exhaust valve housings 18 and 33 are collocated in pairs, as will be understood from Figs. 1 and 4, and the pendant walls 43*, which are carried by the head 7, contact with the machined top 6 as seen in Fig. 4 and isolate each pair of piston valves 17 and 31 from the other pairs of valves. The open ended tubular extensions or housings 18 and 33 are preferably cast integral upon the top of the cylinders, but may obviously be secured thereto by other means.

As will be apparent from Figure 2 in a preferred embodiment of my invention I construct the lower end of the inlet valve rod 16 so that it has threaded engagement with the yoke 44 whereby the distance between the valve and the cam shaft can be ad-

justed according to requirements, the lock nut 45 serving to lock the rod and the yoke in the desired fixed position after adjusting. The exhaust valve rod 32 is likewise threaded at its lower end as indicated at 46 so that it can be adjustably secured to the yoke 47, the parts are in their desired adjusted position being locked by the lock nut 48 which has the same function as the lock nut 45.

10 Having thus described my invention, what I claim as new and desire to secure by Letters Patent, is:—

In a device of the character stated, an engine cylinder, an inlet chamber and an ex-

haust chamber at the side thereof, tubular, 15 open ended inlet and exhaust valve housings integral with said cylinder and located above said chambers and at their bottom in communication therewith, and each having a pair of opposed side ports opening into the 20 explosion chamber of said cylinder, imperforate inlet and exhaust piston valves reciprocable in said valve housings, means for reciprocating said valves, and a head for 25 said cylinder having pendant walls for isolating a pair of said valves from an adjacent pair.

WILLIAM C. GRAY.
